UNITED STATES PATENT OFFICE.

MOSES C. JOHNSON, OF HARTFORD, CONNECTICUT, ASSIGNOR TO THE HELIX GEAR COMPANY, OF SAME PLACE.

DESIGN FOR A BICYCLE-FRAME.

SPECIFICATION forming part of Design No. 31,320, dated August 1, 1899.

Application filed July 5, 1899. Serial No. 722,883. Term of patent 14 years.

To all whom it may concern:

Be it known that I, MOSES C. JOHNSON, a citizen of the United States, and a resident of Hartford, in the county of Hartford and State of Connecticut, have invented a new and original Design for Frames for Bicycles; and I do hereby declare the following, when taken in connection with the accompanying drawings, to be a full, clear, and exact description of the same, and said drawings constitute part of this specification, and represent, in—

Figure 1, a view in side elevation of a frame embodying my design; Fig. 2, a view in front elevation of the gearing-cover at the lower part of the frame, and Fig. 3 a view in rear elevation of the gearing-cover.

My invention relates to a design for the frame of a bicycle of the drop-frame type and in which there is a triangular rear portion *a* and a narrow front portion *b*—that is, one in which the component parts of the frame lie near each other and extend practically in the same direction. The central member *c* inclines upward and backward, rises from the circular central portion *d*, and is united near its upper end to the member *e*, which at its lower end terminates in the circular portion *f*, the parts *d* and *f* being united by the member *g*.

From this central part *d* two members *h* and *i* extend upward and meet the short member *k*. The lower ends of these members *h* and *i* as to their outer lines merge into the lines which define the circular part *d*, so that the front portion *b* of the frame terminates at its forward end in a straight member and at its lower end in the circular member, giving a distinct and peculiar character to this portion of the frame. Below the circular members *d* and *f* circular enlargements *d'* and *f'*, arranged transversely of the larger members and united to each other at their peripheries, are located.

The essential feature of the design resides in the circular member at the center of the lower part of the frame, with the two members of the front portion having their outer lines merging into the circular outline of the central part.

Having described my invention, what I desire to secure by Letters Patent is—

The design for a bicycle-frame substantially as herein shown and described.

MOSES C. JOHNSON.
